UNITED STATES PATENT OFFICE.

MARQUIS J. TODD, OF BUFFALO, NEW YORK, ASSIGNOR TO BUFFALO PITTS COMPANY,
OF BUFFALO, NEW YORK, A CORPORATION OF NEW YORK.

GUIDING MEANS FOR WHEELED VEHICLES.

1,096,576.

Specification of Letters Patent. Patented May 12, 1914.

Application filed April 23, 1913. Serial No. 763,137.

To all whom it may concern:

Be it known that I, MARQUIS J. TODD, of Buffalo, in the county of Erie and State of New York, have invented certain new and useful Improvements in Guiding Means for Wheeled Vehicles; and I do hereby declare the following to be a full, clear, and exact description of the invention, such as will enable others skilled in the art to which it appertains to make and use the same:

The primary object of this invention is to provide simple and highly efficient improved means for connecting the pivoted axles of wheeled vehicles to insure the turning of the axles in opposite direction when the vehicle is traveling on a curve.

A further object is to avoid undue strain on the reach or connection between the axles consequent upon any of the carrying-wheels 20 engaging an obstruction or entering a ditch. And a further object is to insure the ready and easy turning of all the axles by guiding means locked to either of the axles.

In the accompanying drawing, Figure 1 is 25 a plan view with the body of the vehicle removed. Fig. 2 is a side elevation. Fig. 3 is an end elevation. Fig. 4 shows a slight modification especially adapted for dumping wagons where an open bottom is required.

Referring to the drawings, 1 designates the chassis; 2 the pivoted stub-axles; 3 the carrying wheels; and 4 frames connecting the complementary stub-axles. According 35 to the form shown in Figs. 1 to 3 this frame is composed of a cross-bar pivoted at its ends to inwardly projecting arms 5 extending from the pivoted ends of the stub-axles, said cross-bar extending transversely of the 40 vehicle. One of the arms 5 of each pair of axles is elongated, that is, it has an extension 6 to which a link 7 is connected by a universal joint 8.

9 designates a crank-shaft having its bearings on the chassis and extending longitudinally thereof. The depending crank arms, at the ends of the shaft, are connected by universal joints to the inner ends of links 7. Hence, as either pair of stub-axles is turned 45 on their pivots the other axles will be turned in the opposite direction, the movement of one pair of axles being communicated to the other pair through the instrumentality of the crank-shaft. In this way the carrying 50 wheels may be shifted in opposite directions.

for turning a curve, and to enable the vehicle to be moved in reverse direction.

To outwardly projecting arms 10 of the stub-axles I connect, by means of universal joints, the ends of a cross-bail 12 which is 60 shown as curved outwardly from a direct line between its pivoted connections to said arms. These bails 12 carry racks 13 with which coupling members 14 are designed to be locked. As pointed out in my application for patent filed April 22, 1913, Serial No. 762,825, the coupling members consist of bars which are pivoted at 15 to the chassis, at the longitudinal center thereof, and each coupling bar carries locking means for 65 engaging the respective rack 13. It is customary, in trains of wheeled vehicles to lock the coupling member to the forward end of each succeeding vehicle, and, when it is desired to reverse the direction of travel, the 70 coupling members are unlocked from one vehicle of each pair and locked to the other or next adjacent vehicle, but inasmuch as this forms the subject matter of my before noted application further reference thereto 75 is unnecessary, other than to say that while I have shown the vehicle as provided with a coupling member at each end only one of these members is locked at a time to such vehicle, the selection depending upon the 80 direction of travel. When the coupling member which is locked to the vehicle is shifted laterally, as in turning a curve, power is communicated through bail 12 to the pivoted 85 axles, causing such axles to turn on their pivots to shift the carrying wheels, and the turning of either pair of axles is, through the frames and crank-shaft, communicated 90 to the other pair of axles.

The outwardly bent bails 12 being flexibly 95 connected to arms 10 are free to rise and fall upon encountering obstructions in the road, without any undue strain thereon, allowing each rack to remain in proper relation to its coupling member under all conditions.

Although I prefer to connect the stub axles of each pair through the frame 4, yet it is manifest that if desired the cross-bar of this frame and the shorter of the two arms 5 may be omitted, since the necessary 100 co-action between complementary axles will be effected through the connection formed by the bail 12. It is necessary, however, to retain the other arm to which the link 7 is 105 connected.

In Fig. 4 I have shown one of the features of my invention applied to a vehicle having centrally pivoted axles in lieu of the stub-axles which latter are especially adapted 5 for automobile construction. The crank shaft 9 is shown as located near one side of the chassis so as to leave an open bottom when required for dumping purposes. The links 7 are connected to frames 16 which 10 latter are shown as secured to the respective axles at points near their outer ends, equal distances from their central pivots. These 15 frames 16 are preferably fixedly secured to the axles, and in line therewith are outwardly projecting bars 17 which carry the locking racks 13. According to the form shown in Fig. 4 the shifting of either of the pivoted axles will be communicated to the other axle through the instrumentality of 20 the inwardly extending frames 16 and the crank shaft.

The advantages of the present invention will be readily appreciated. It will be noted that the single crank shaft constitutes a reach; that it serves to readily communicate movement between the axles, causing them to operate in unison; and that it may be employed with advantage in a vehicle having an open bottom dump. It will 25 also be noted that in those vehicles embodying pivoted stub-axles the two axles of each pair will be caused to move uniformly, and that by connecting either axle to the crank shaft the shifting of both axles of each pair 30 may be effected.

I have shown, in most instances, ball-and-socket connections between the various parts, and I prefer to use such construction, but it is manifest that other forms of universal-joints may be employed, and likewise changes in the details, construction and arrangement of parts may be made without departing from my invention.

I claim as my invention:

45 1. A wheeled vehicle having pivoted axles, frames extending inwardly from and connected to said axles, a crank-shaft extending longitudinally of the vehicle and connected to said frames for causing the 50 axles to move in unison in opposite directions, and guiding members projecting be-

yond the ends of the vehicle and capable of being locked to the pivoted axles.

2. A wheeled vehicle having pivoted axles, frames extending inwardly from and 55 connected to said axles, guiding members projecting from the ends of the vehicle, locking members connected to the pivoted axles and to which said guiding members are designed to be locked, a crank-shaft extending longitudinally of the vehicle, and means connecting said crank-shaft to said frames.

3. A wheeled vehicle having pivoted 60 stub-axles, means connecting the axles of each pair of axles, a crank-shaft extending longitudinally of the vehicle and connected to one of the axles of each pair of axles, and guiding members projecting beyond the ends of the vehicle and capable of being 65 locked to the pivoted axles.

4. A wheeled vehicle having pivoted 70 stub-axles, outwardly extending cross-members pivoted to opposite stub-axles, guiding members projecting from the ends of the 75 vehicle, means for locking either guiding member to one of said outwardly-extending members, and a crank-shaft extending longitudinally of the vehicle and connected at its ends to one stub-axle of each pair of 80 axles.

5. A wheeled vehicle having pivoted 85 stub-axles, outwardly extending cross-members pivoted to opposite stub-axles, guiding members projecting from the ends of the 90 vehicle, means for locking either guiding member to one of said outwardly-extending members, said stub-axles having inwardly projecting arms, cross-rods connecting said arms of the axles of each pair, and a crank-shaft extending longitudinally of the vehicle and connected at its ends to the inwardly extending arm of one axle of each pair.

In testimony whereof, I have signed this 95 specification in the presence of two subscribing witnesses.

MARQUIS J. TODD.
